UNITED STATES PATENT OFFICE

ISAAC E. HANSON, OF OKLAHOMA CITY, OKLAHOMA

AEROPLANE

Application filed April 9, 1928. Serial No. 268,571.

The present invention relates generally to aeroplanes and has for its prime object to provide means for preventing the formation of ice on the wings of the aeroplane.

Other very important objects of the invention reside in the provision of means whereby the heat generated by the exhaust of the engine of the aeroplane may be utilized to prevent the formation of the ice on the wings.

A still further very important object of the invention resides in the provision of an improvement of this nature which is simple in its construction, inexpensive to install, strong and durable, and thoroughly efficient and reliable in use and otherwise well adapted to the purpose for which it is designed.

With the above and numerous other objects in view as will appear as the description proceeds, the invention resides in certain novel features of construction and in the combination and arrangement of parts as will be hereinafter more fully described and claimed.

In the drawings:

Figure 1 is a top plan view of an aeroplane embodying the features of my invention.

Figure 2 is a front elevation thereof.

Figure 3 is a fragmentary side elevation thereof.

Figure 4 is a sectional view through the air drum and exhaust pipe.

Figure 5 is a sectional view through one of the wings and the air chamber thereon, and

Figure 6 is a detail section taken through one of the conduits.

Referring to the drawing in detail, it will be seen that the numeral 5 denotes an aeroplane fuselage, having wings 6 and 7 mounted thereon in the usual well known manner.

On the wings 6 and 7 there are mounted respectively air chambers 8 and 9, formed of sheet metal. Pipes 10 connect the air chambers 8 and 9 together. Branches 11 lead inwardly from the pipes 10 intermediate their ends and communicate with the drum 12 disposed about exhaust manifolds 14 leading from the engine 15. A pipe 16 leads from the exhaust manifold along the top of the fuselage 5 and terminates adjacent the rear controls 17, to prevent the formation of ice

thereon. The exhaust heating up the exhaust pipe 14 will heat the air in the drum 12 and cause it to circulate through branches 11 and pipes 10 into the chambers 8 and 9 which will be sufficiently heated to prevent the formation of ice thereon in rainy and snowy weather.

It is thought that the construction, utility and advantages of this invention will now be quite apparent to those skilled in this art without a more detailed description thereof.

It is apparent that the present embodiment of the invention has been disclosed in considerable detail merely by way of example, since in actual practice it will retain the features of advantage enumerated as desirable in the statement of the invention and the above description.

It will be apparent that changes in the details of construction and in the combination and arrangement of parts may be resorted to, without departing from the spirit and scope of the invention as hereinafter claimed or sacrificing any of its advantages.

Having thus described my invention, what I claim as new is:

1. In an aeroplane of the class described, a fuselage, a pair of wings mounted on the fuselage, air chambers on the wings, pipes connecting the air chambers, branches leading inwardly from the pipes, an exhaust pipe, a drum about the exhaust pipe with which the branches communicate, a pipe connected with the exhaust pipe and extending along the top of the fuselage rearwardly to terminate at the rear end thereof.

2. An aeroplane comprising a fuselage, an exhaust pipe in the fuselage, a drum disposed about the exhaust pipe, a pair of wings, an air chamber on each of said wings and extending for the full length thereof, piping connecting these air chambers, branches on the piping communicating with the drum, a pipe leading from the exhaust pipe and extending exteriorly of the fuselage along the top of the same to terminate at the rear end thereof.

In testimony whereof I affix my signature.

ISAAC E. HANSON.
